UNITED STATES PATENT OFFICE

JOSEPH W. BRAGSTAD, OF ELMHURST, ILLINOIS

FORCED-DRAFT-PRODUCING DEVICE

Application filed April 17, 1929. Serial No. 355,789.

This invention relates to improvements in devices for producing forced drafts, particularly adapted though not necessarily limited in its use, for hot air furnaces, and 5 one of the objects of the invention is to provide improved means for drawing cold air out of a house or room and for forcing warm air thereinto.

A further object is to provide an improved 10 device of this character having means to prevent what is commonly known as "back lash" of the air, to prevent the heated air from obstructing or forcing back the inflow of cold air, and thereby insure a circulation of the air.

A further object is to provide an improved filter device for the air supply to the fan.

To the attainment of these ends and the accomplishment of other new and useful objects 20 as will appear, the invention consists in the features of novelty in substantially the construction, combination and arrangement of the several parts hereinafter more fully described and claimed and shown in the accompanying drawings illustrating this invention and in which

Figure 1 is a view partly in elevation and partly in section of a device of this character constructed in accordance with the principles of this invention and showing the same as used in connection with a flue and with parts omitted.

Fig. 2 is a view taken on line 2-2, Figure 4, with parts omitted.

Figure 3 is a view similar to Figure 2, showing the operating mechanism for the dampers.

Figure 4 is a sectional view taken on line 4-4, Figure 2, with parts in elevation.

Figure 5 is an enlarged detail sectional view taken on line 5-5, Figure 1.

Figure 6 is an enlarged detail sectional view showing the manner of securing the filter casing to the fan casing.

Referring more particularly to the drawings the numeral 10 designates generally a flue of any desired size and configuration for receiving and conducting cold air away from a room or house. This flue 10 may have 45 communication with a room through the

floor 11 thereof and by means of the ordinary air registers or grating 12.

The flue may be of any desired size and configuration and communicating therewith may be additional flues 13-14 leading from 55 other points of supply of cold air.

Arranged adjacent the bottom of the flue in an opening 15 and suitably supported is a casing 16 which has communication with the opening 15 at one end, and is provided with 60 an outlet opening 17 through which latter air circulated through the flue 10 will be directed to a furnace.

The casing 16 is of any desired size and configuration but is preferably angular in 65 cross section and arranged within the casing 16 is a fan casing 17 which is of a diameter to occupy only a portion of the cross sectional area of the casing or passage 16.

The fan casing 17 is preferably circular 70 in cross section and in order that it may conform to the contour of the casing or passage 16 filler members 18 may be formed on the outside of the fan casing.

Uprights 19 may be arranged in the casing 75 or passage 16 to abut the portions 18 of the fan casing and also the periphery of the latter for holding the fan casing in position.

The fan casing 17 preferably projects beyond the casing or passage 16 at the entrance 80 end of the latter and arranged in the fan casing is a motor 20 for operating the fan 21.

The motor may be supported in any suitable manner preferably by means of brackets 85 22 which pass through suitable openings 23 in the bottom of the casing or passage 16 and are embedded in plastic material 24 such as cement, concrete or the like, the free extremities of the brackets 22 being preferably deflected as at 25 to form anchors for the brackets.

Encompassing the anchoring material 24, which latter may be arranged within the ground 26, is a filling material such as sand, 95 gravel or the like.

The openings 23 in the wall of the casing or passage 16 are of a size somewhat greater than the dimensions of the brackets 22 so that the brackets will be held out of contact with 100

the walls of the opening to prevent vibration of the brackets against the casing wall. Similarly the fan casing 17 is provided with openings through which the brackets 22 pass and these openings are also of a size to prevent the walls of the opening from contacting with the brackets.

Arranged in the casing or passage 16 and between the uprights 19 and the lateral walls 10 of the casing or passage 16, are dampers 28 which are swingingly supported by means of suitable hinges 29 and springs 30 may be provided, one end of which is secured to the respective dampers 28 and the other end of each 15 is anchored as at 31 to a fixed support preferably the upright walls of the casing or passage 16.

These springs 30 tend normally to move the dampers 28 in a direction to close the 20 passage between the fan casing and the outer casing or passage 16, suitable stops 32 being provided for limiting the movement of the dampers 28 under the stress of the springs 30.

25 The dampers 28 are provided to prevent a "back lash" of the heated air currents and to prevent the heated air from interrupting or obstructing the flow of cold air currents through the passage or casing 16.

30 Flexible members 33 are connected with the dampers 28 and these members in turn may be connected to a control element 34 by means of which the dampers 28 may be operated from a remote point and against the 35 stress of the springs 30. The operation of the dampers 28 will, through the medium of spaced stops 35 on the member 34, operate upon a switch lever 36 to control the operation of a switch 37, which in turn controls the operation of the motor.

40 It has been found in devices of this character that the fan causes considerable dust and foreign matters to be drawn from the room and discharged through the fan casing.

45 In order to overcome this objection there is provided a tubular filter 38 which is constructed of any suitable flexible material. The end 39 of the filter is preferably closed while the end 40 thereof is open. This open 50 end 40 of the filter telescopes over a flange 41 on the inlet end of the fan casing 17 and a suitable fastening means such as a draw string, or other suitable element, may be provided for holding the end of the filter 39 55 against accidental detachment from the flanged end 41 of the fan casing 17.

60 The filter 38 may be of any desired length and projects for a considerable distance beyond the inlet end of the fan casing so as to enter and be disposed within the flue 10.

65 A flexible member 43 is connected by one end as at 44 with the end of the filter and the flexible member passes over pulleys 45-46, within the flue 10 to another pulley 47 adjacent the bottom of the flue so that the end

39 of the filter may be raised and lowered within the flue 10 and maintained in its adjusted position. An opening 48 is provided in the flue 10 and is closed by means of a closure 49 and through the medium of which closure 49 and opening 48 access may be had to the filter to remove the same when desired.

70 An anchor 50 may be provided for anchoring a portion of the filter so that it will not be drawn into the flue and to prevent it from becoming detached from the fan casing 17.

If desired and in order to maintain the 75 filter against collapsing rings 51 constructed of any suitable material, are provided and are arranged at spaced intervals in directions lengthwise of the filter.

These rings may be secured in position in any suitable manner such as by means of a 80 fastening device 52 such as a flexible member or the like and the rings may be arranged either on the inside or the outside of the filter.

85 The filter is of a diameter considerably less than the internal diameter of the flue 10 so that the air currents being drawn into the flue 10 will pass into the filter 38 from the outside thereof and throughout the length 90 of the filter.

95 With this improved construction it will be manifest that by adjusting the dampers 28 the circulation of the air currents may be controlled and by the provision of the filter 100 the air will be filtered before it reaches the fan.

105 The filter being extended, presents an extended surface through which the air may be filtered and being flexible may be raised and lowered in the flue to any desired height 110 and may be readily removed from the flue and detached from the fan casing 17 through the door opening 48.

115 It has been found that by locating the fan 21 in a position that it will project or stand slightly beyond the outlet end of the casing or in a position where it will be in close proximity to the end but spaced slightly therefrom, the air currents will be thrown out radially toward the wall of the casing or 120 passage 16, with the result that the air will be equally distributed at all points around the base of the furnace with which the casing or passage 16 has communication.

125 If the air currents are not so distributed, but if they leave the fan casing in a direct line with the fan, the air currents will strike one spot or area on the fire pot wall, with the result that the wall will warp and there will be a leak. That is, it will be hotter on the two sides or areas which are not contacted by the direct blast of air.

130 While the preferred form of the invention has been herein shown and described, it is to be understood that various changes may be

made in the details of construction and in the combination and arrangement of the several parts, within the scope of the claims, without departing from the spirit of this invention.

5 What is claimed as new is:—

1. An apparatus of the character described embodying an air passage, a fan casing occupying only a portion of the cross sectional 10 area of the passage, and a tubular filter fitting over and forming a closure for the inlet end of the fan casing, the inlet of the fan casing being disposed adjacent a flue and into which flue the said filter projects beyond 15 the fan casing.
2. An apparatus of the character described embodying an air passage, a fan casing occupying only a portion of the cross sectional area of the passage, a tubular flexible filter fitting over and extending beyond the fan casing and into a flue, means for supporting the free end of the filter in the flue, and means for maintaining the filter against collapsing. 20
3. In combination an extended flue, a fan casing adjacent and having communication with the flue, a tubular flexible filter open at one end, said end being secured to and having communication with the inlet end of the fan casing to form a closure therefor, said filter extending into the flue beyond the fan casing, and means for raising and lowering the end of the filter in the flue and for supporting said end of the filter. 30

In testimony whereof I have signed my name to this specification, on this 12th day of April, A. D. 1929.

JOSEPH W. BRAGSTAD.
